HYDROTHERAPY UNIT FOR BATH TUBS

Henry J. Talge, Leawood, and James M. Gerdom, Over-
land Park, Kans., assignors to Whirl-O-Matic Corpo-
ration, Kansas City, Mo.

Filed Sept. 5, 1975, Ser. No. 610,618

Term of patent 14 years

Int. Cl. D24—01

U.S. Cl. D83—1 C

Fig. 1.

Fig. 2.

Fig. 3.

Fig. 4.

Fig. 5.

Fig. 6.

Fig. 7.

FIG. 1 is a front perspective view of a hydrotherapy unit for bath tubs showing our new design;

FIG. 2 is a side elevational view of same taken from the side seen in FIG. 1;

FIG. 3 is a top plan view of same;

FIG. 4 is a side elevational view of same showing the side opposite that shown in FIG. 2;

FIG. 5 is an end view of same taken from the left end as viewed in FIG. 4;

FIG. 6 is an end view of same taken from the right end as viewed in FIG. 4; and

FIG. 7 is a bottom plan view of same.

We claim:

The ornamental design for a hydrotherapy unit for bath tubs, as shown.
